(57) **CLAIM**

The ornamental design for a networking device for a streetlight, as shown and described.

DESCRIPTION

FIG. 1 is a perspective view of a networking device for a streetlight showing our new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof; and,

FIG. 7 is a right side elevational view thereof.

The dot-dot-dash broken lines in FIGS. 1–4, 6, and 7 define the boundaries of the claimed design. All other broken lines illustrate an environment and form no part of the claimed design.
